Assistant Examiner — Bethany Louise Mallino

CLAIM

The ornamental design for a upright freezer cover, as shown and described.

DESCRIPTION

FIG. 1 is a perspective view of a upright freezer cover design showing my new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof; and,

FIG. 8 is a perspective view showing the doors in an open position.

The broken lines show a upright freezer cover for illustrative purposes only, and form no part of the claimed design.

1 Claim, 8 Drawing Sheets(56)
